UNITED STATES PATENT OFFICE.

GEORGE D. CLARDY, OF ALLWOOD, NEW JERSEY.

DESIGN FOR A STATUETTE.

60,778.

Specification for Design. Patented Apr. 11, 1922.

Application filed December 2, 1921. Serial No. 519,528. Term of patent 14 years.

To all whom it may concern:

Be it known that I, GEORGE D. CLARDY, a citizen of the United States, and a resident of Allwood, in the county of Passaic and State of New Jersey, have invented a new, original, and ornamental Design for a Statuette, of which the following is a specification, reference being had to the accompanying drawing, forming part thereof.

Figure 1 is a front elevation of a statuette showing my new design.

Figure 2 is a side view of the statuette shown in Figure 1.

Figure 3 is a rear view of the statuette shown in Figure 1.

What I claim is:

The ornamental design for a statuette, as shown.

GEORGE D. CLARDY. [L.S.]
